UNITED STATES PATENT OFFICE.

PERLEY R. GLASS, OF BROOKLINE, MASSACHUSETTS, ASSIGNOR TO P. R. GLASS COMPANY, OF BOSTON, MASSACHUSETTS, A CORPORATION OF MASSACHUSETTS.

FOLDING-MACHINE.

1,281,556.

Specification of Letters Patent. Patented Oct. 15, 1918.

Application filed January 18, 1915. Serial No. 2,874.

To all whom it may concern:

Be it known that I, PERLEY R. GLASS, a citizen of the United States, residing at Brookline, in the county of Norfolk and State of Massachusetts, have invented certain Improvements in Folding-Machines, of which the following description, in connection with the accompanying drawings, is a specification, like reference characters on the drawings indicating like parts in the several figures.

This invention relates to machines for folding in a step-by-step manner pliable material such as parts of boots and shoes. 15 Machines of this kind include folding instrumentalities which partially or completely form the fold and pressing instrumentalities which press the fold after it has been formed.

20 The action of the folding instrumentalities in many cases temporarily bends the work at right angles to its margin or strains the work as if it had been so bent. As a result of this action the work heretofore operated upon has had a tendency to curl up when taken out of the machine. Work in this conditions has an appearance which is objectionable and is also somewhat awkward for the sewing machine operator who stitches together the parts of the upper. In accordance with an important feature of the present invention means are provided for eliminating from the work this tendency to curl up so that the work will be in a flat condition 30 when it leaves the machine. As herein shown the desired result is effected by providing coöperating work engaging means which impart to the work temporarily a sharp bend in a direction opposite to the 35 transverse bending caused by the action of the folding instrumentalities. For example, it has been found that if the folding instrumentalities bend the work upwardly and at right angles to its margin, means which 40 bend the work downwardly and at right angles to its margin will be effective to remove entirely from the work any tendency to curl up.

45 As herein shown the work engaging means for bending the work downwardly comprise the hammer and anvil which have also the function of the pressing instrumentalities

above discussed. These elements in the construction herein shown also have the function of feeding the work. The utilization of 55 the hammer and anvil for the three functions of bending, pressing and feeding the work, constitutes an important feature of the present invention although it will be understood that it is within the scope of the 60 invention to provide separate work bending elements or so to modify any other elements than the hammer and anvil which are now commonly used in folding machines of this 65 class, that the said elements may perform the bending function.

One form of anvil suitable for producing the desired results has two flat work engaging faces disposed at different levels and separated by a step or shoulder over which 70 the work may be bent by the hammer. Such an anvil constitutes a further feature of the invention.

Still other features of the invention relate 75 more particularly to the construction of the individual work pressing elements. For purposes of adapting the hammer and anvil to operate on work of various thicknesses the stepped work engaging faces of one of said elements are made relatively adjustable so 80 that the height of the shoulder or step may be varied to suit the conditions of the work in hand. As herein shown this adjustment is provided for in the hammer. A bent or angular groove is also provided in one face 85 of the hammer to facilitate plaiting the work about convex edges.

Another feature of the invention relates to improved mechanism for operating the hammer whereby the action of the latter 90 may be made resilient to accommodate work of varying thickness and at the same time afford convenient provision for adjustment of the tension of the hammer operating mechanism and of the path of the hammer. 95

These and other features of the invention will be best understood and appreciated from the following description of a preferred embodiment thereof selected for purposes of illustration and shown in the accompanying drawings in which,—

Figure 1 is a view in perspective of the operative parts of a folding machine showing the hammer in its raised position;

Fig. 2 is a similar view showing the action of the hammer and anvil upon the work;

Fig. 3 is a view in perspective of the hammer and its actuating mechanism;

Fig. 4 is a view of a portion of this mechanism partly in section, and

Fig. 5 is a view in perspective of the work engaging face of the hammer.

10 The invention is herein illustrated as embodied in a folding machine of the type disclosed in my pending application Serial No. 790,892, filed September 20, 1913, but it will be understood that the invention is in 15 no way restricted to this or any particular type of folding machine. The application herein mentioned, however, discloses one form of specific mechanism desirable for operating the instrumentalities herein illustrated and for further details of construction reference may be had to said application.

Referring to Figs. 1 and 2, 10 indicates the table of the machine above which projects an arm 12 carrying a creasing member 14 the inner edge of which acts to determine the line of fold in coöperation with a reciprocating folding member 16. The member 16 moves up and down in an inclined 30 path opposite to the edge of the creaser and turns the margin of the work up about the edge of the creaser in a step-by-step manner. Underlying the creaser 14 is a clamping block 18 between which and the creaser the work is held during the action of the folder 16. The arm 12 also carries an oscillating snipping knife 17 which may be used or not as desired.

The hammer and anvil are arranged to 40 act upon the work after it passes the folder and creaser. The anvil 20 is disposed on the left hand side of the clamping block 18 and has a work engaging face 22 disposed at substantially the same level as the face of 45 the clamping block 18 and a second work engaging face 24 disposed at a slightly lower level and being separated from the face 22 by a step or shoulder 26 which extends substantially at right angles to the edge of the 50 work. Arranged to coöperate with the anvil is the hammer 28 which has a portion 30 with a face shaped to coöperate with the flat face 22 of the anvil and a portion 32 having a face disposed below the face of the 55 portion 30 and arranged to coöperate with the face 24 of the anvil. The portion 32 of the hammer is adjustably secured in place by screws 34 and these permit adjustment of the relative position of the work engaging 60 faces of the portions 30 and 32 of the hammer.

The action of the hammer and anvil upon the work is well shown in Fig. 2 from which it will be noted that the hammer acts to

draw both plies of the completed fold over 65 the step or shoulder 26, forcing it down upon the lower face 24 of the anvil and thus bending the work sharply downwardly and at right angles to its edge. The face 24 constitutes in effect a recess formed in the anvil 70 while the portion 32 of the hammer acts to bend the work into the recess. The bend in the work appears above the shoulder 26 in Fig. 2 and this bend, as already intimated, serves to counteract the strain in the work 75 which has been caused by the bending in the opposite direction to which the work has been already subjected by the action of the folding instrumentalities.

As herein shown, the hammer and anvil 80 are given an intermittent feeding movement toward the left, Fig. 1, while in engagement with the work to feed the work through the machine. The mechanism for imparting the transverse feeding movement to the hammer 85 and anvil is not herein shown but may correspond to that disclosed in my prior application hereinbefore identified. To facilitate starting the work the hammer 28 is provided with a spring foot 36 which extends forwardly from the hammer in the direction of the feed and acts to engage the advancing edge of the work before the latter has come into range of the main portions of the hammer and anvil. The anvil 20 is provided 90 with a forwardly extending projection 38 which coöperates with the spring foot 36 and is arranged to slide in a slot formed in the clamping block 18.

The work engaging surface of the portion 100 30 of the hammer 28 is provided with a groove or slot 31 as shown in Fig. 5 for the purpose of standardizing the plaits or puckers formed in rounding the convex curved edges of the work. As herein shown the slot 31 105 comprises two portions which make a slight angle with each other. The inner portion is disposed substantially normal to the margin of the work being operated upon while the outer portion is inclined at its front end 110 slightly in a direction to meet the oncoming work. A slot of this shape has been found to facilitate the forming of the plaits and render them more uniform in size.

The hammer 28 is oscillated by a cam 115 shaft 40, shown in Fig. 3, through mechanism which will now be described. The hammer is pivoted for movement about the axis of a journal member 42 and has a forwardly extending arm secured to or formed 120 integral with a casing 44 herein shown as of substantially square cross-section. One side and the bottom of the casing are formed by an angle plate 46 having an arm 48 which extends upwardly and over the top of the 125 casing as shown in Fig. 3. Within the casing is disposed a hollow plunger 50 having an arm 52 which extends outwardly through

the casing and is pivotally connected to an actuating link 54. Within the plunger is located a compression spring 56 which rests on the bottom of the casing and normally holds the plunger 50 in its elevated position. The normal position of the plunger 50 is determined by an adjusting screw 58 threaded into the arm 48 of the casing. An adjusting screw 60 passes through the top of the plunger 50 and is provided with a head for engaging the upper end of the spring 56. By means of the screw 60 therefore the degree of compression of the spring 56 may be regulated.

15 The link 54 is connected through a second link 62 with an oscillating cam lever 64 which is actuated by a cam 66 on the cam shaft 40. The oscillation of the cam lever 64 is therefore transmitted through the links 62 and 54 to the plunger 50 and thence through the spring 56 to the casing 44 which is formed rigidly with the hammer 28. If a thick place is encountered in the work, and the hammer thereby prevented 25 from reaching its lowest position, the spring 56 will yield to permit the normal movement of the plunger 50 caused by its driving connection with the cam lever 64. The initial position of the hammer may be adjusted by means of the adjusting screw 58 as already stated while its pressure on the work may also be regulated by varying the compression of the spring 56 through the adjusting screw 60.

35 Although in the illustrative machine the hammer and anvil have been shown as constructed to bend the folded margin downwardly approximately at a right angle, it should be understood that the important 40 feature is the downward bend during the pressing operation, and that the particular angle of the bend or whether there is strictly any angle at all is not essential.

45 Certain features herein shown, such for example as an anvil having different localities in its operative face located at different levels, a groove in the hammer to receive the puckers, and a spring finger to start the feed of the work, are claimed broadly 50 in my prior application which has been referred to above.

Having thus described my invention, I claim as new and desire to secure by Letters Patent of the United States:

55 1. A folding machine, having, in combination, folding instrumentalities constructed and arranged to turn upwardly and fold the margin of the work, and means for bending downwardly the folded edge about a line extending at right angles to its margin.

60 2. A folding machine, having, in combination, folding instrumentalities constructed to operate in a step-by-step manner to turn upwardly and fold over the margin of the

work, and means constructed and arranged 65 to act subsequently upon the margin so folded to bend the material of both plies of the folded margin downwardly.

3. A folding machine, having, in combination, feeding, folding and pressing instrumentalities including a coöperating presser 70 and anvil shaped to impart a downward bend to both plies of the folded margin during the pressing operation.

4. A folding machine, having, in combination, feeding instrumentalities, and work 75 pressing means shaped to bend the fold about a line extending at right angles to the margin of the work during the pressing operation.

5. A folding machine, having, in combination, folding instrumentalities constructed and arranged to turn up and fold over the margin of the work, and feeding devices shaped to engage the work and bend the 85 folded margin downwardly during the feeding operation.

6. A folding machine, having, in combination, folding and pressing instrumentalities including an anvil with two work engaging 90 surfaces disposed at different levels against both of which the folded margin of the work is pressed.

7. A folding machine, having, in combination, folding and pressing instrumentalities 95 including a hammer and anvil with opposed faces constructed and arranged to bend the work about a line extending at right angles to its margin.

8. A folding machine, having, in combination, work feeding and pressing instrumentalities including an anvil having its work engaging face stepped down in the direction of feed.

9. A folding machine, having, in combination, work feeding and pressing instrumentalities including an anvil having a recess with an edge extending at right angles to the direction of feed, and means to bend the work over said edge.

10. A folding machine, having, in combination, folding and pressing instrumentalities including a hammer movable up and down above the work and having an operative portion thereof adjustable relatively 115 to a second operative portion toward or from the work.

11. A folding machine, having, in combination, folding and pressing instrumentalities including an anvil having a portion 120 of its work engaging surface depressed, and a hammer having an adjustable portion disposed in opposition to the depressed surface of the anvil.

12. A folding machine, having, in combination, folding and pressing instrumentalities including a hammer divided at right angles to the margin of the work into sec-

tions, the sections thereof being relatively adjustable.

13. A folding machine, having, in combination, folding and pressing instrumentalities including a hammer having a work engaging face with a bent pucker-receiving slot formed therein.

14. A folding machine, having, in combination, a hammer having a work engaging face with a bent pucker-receiving slot formed therein of which one portion is disposed substantially at right angles to the margin of the work.

15. Pressing mechanism for a folding machine including coöperating work pressing members each having two stepped work engaging faces, and one member having its stepped faces relatively adjustable.

16. Pressing mechanism for a folding machine comprising a hammer pivoted to the frame of the machine and having secured

rigidly thereto a hollow casing, a hollow plunger disposed within the casing, a spring disposed within the plunger and bearing upon the casing, and actuating mechanism 25 connected to the plunger.

17. Pressing mechanism for a folding machine comprising a hammer having secured rigidly thereto a hollow casing, a plunger extending into and fitting the inside of the casing, a spring between said plunger and casing; means for varying the tension of said spring, and means for adjusting the position of the plunger relatively to the casing.

In testimony whereof I have signed my 35 name to this specification in the presence of two subscribing witnesses.
